METHOD OF AND APPARATUS FOR VACUUM
SEALING CONTAINERS

Karl L. Ford, Durham, N. H., assignor of one-third to William B. Wilcutt, Fitchburg, N. Y., and one-third to Edmund M. Sawtelle, York, Maine

Application May 24, 1937, Serial No. 144,415

7 Claims. (Cl. 226—82)

The general object of the present invention is to provide an improved method of and apparatus for automatically sealing so-called vacuum sealed jars or containers, such, for example, as those disclosed in United States Patents, Nos. 1,862,560, and 1,963,101, and used to enclose fruits, vegetables, and other foodstuffs to be preserved and materials desirably held. More specifically, the object of the invention is to provide for the effective and rapid sealing of vacuum sealed containers, by subjecting each container, after it has been filled and has had its cover loosely put in place, to a top heating action which is confined wholly or mainly to the upper portion of the container and its cover, and by which air and vapor will be expelled from the container, so that when, as a result of a subsequent cooling or other action, the vapor pressure within the container becomes less than the atmospheric pressure acting externally on the container, the container cover will be forced by the pressure differential into sealing relation with the container.

In many uses of the present invention, the top heating and sealing action will follow container filling, heating, and cover positioning operations carried out in relatively rapid succession, but with opportunity for some cooling of the container between the last mentioned heating operation and the top heating operation characteristic of the present invention. The said heating operation preceding the top heating operation, may or may not be a cooking operation, but in any case will ordinarily result in the expulsion of all, or practically all, of the air previously held in the container or its contents. The cooling occurring during the period in which the cover is being put in place on the container may result in the passage of some air into the upper portion of the container. The top heating operation drives out that air and generates some vapor, with the result that an adequately high vacuum is obtained by a subsequent container cooling action, more quickly than it could be, if the entire container, instead of the top portion only, had been subjected to the heating operation immediately preceding and resulting in the sealing action.

In the preferred practical embodiment of the invention, the top portions of the containers are moved through a top heating chamber on a belt conveyor by which the containers are supported and moved, and on which the containers are distributed in a row, or in a plurality of side by side rows. The same belt conveyor may be used to move the containers progressively through filling,

first heating, and capping stations, or zones, before they reach the container top heating zone. The top heating chamber may be heated by any available and suitable heating means, such as gas burners and electric heaters, or by discharging hot air or steam into the top heating chamber. The latter may be open at its underside, though, in some cases, it may be provided with a movable bottom wall formed by a travelling belt having apertures which receive and are substantially filled by neck portions of the containers moving through the top heating zone.

Of the drawing:

Fig. 1 is a diagrammatic elevation of container filling, heating, capping, and top heating apparatus, with parts broken away and in section;

Fig. 2 is a partial section on the line 2—2 of Fig. 1;

Fig. 3 is a diagrammatic elevation illustrating a modification of the apparatus shown in Figs. 1 and 2;

Fig. 4 is a section on the line 4—4 of Fig. 3; and

Fig. 5 is a plan view of a portion of a belt or apron employed in the apparatus of Figs. 3 and 4.

In the form of the invention illustrated diagrammatically in Figs. 1 and 2, a horizontally extending belt conveyor A, running over pulleys A', gives horizontal movement to a row of containers B, supported on the upper rim of the belt, and thereby moves the top portions of the containers through a top heating chamber C. As shown, the upper run portion of the belt A is supported at its side edges by longitudinal guide rail parts A², and the belt, which may be formed of woven wire or other material commonly employed for the purpose, is transversely stiffened by cleat-like members A³, notched to receive lower portions of the containers B, which are thereby properly positioned on the belt.

The top heating chamber C, as shown, is in the form of a box above, and elongated in the direction of travel of the belt A. The end walls C' of the box C are formed with notches C² in their lower edges, and the bottom wall of the box is formed with a slot C³, for the passage therethrough of the top portions of the containers, which extend to a level above the level of the bottom of the box. As shown, the top heating chamber C is heated by discharging steam into the chamber from perforated steam supply pipes D. As shown, there are two pipes D extending longitudinally of the chamber adjacent the bottom of the latter, and arranged one at each side

of the row of container top portions extending into the chamber.

Before the containers are moved into the top heating zone, the container caps, or cover parts, *b*, are loosely placed on the containers. To prevent displacement of the covers *b*, by the air or vapor expelled from the containers, while at the same time permitting the covers to lift or tilt sufficiently for the escape of air and vapor expelled during the top heating action, I advantageously make use of a conveyor belt *E*, running over pulleys or rolls *E'* in the chamber *C* adjacent the ends of the latter. As shown, the belt *E* carries cover engaging parts or projections *E*² 10 suitably spaced to symmetrically engage the different container covers *b*, and thereby yieldingly hold the latter in place. As shown, lifting of the lower run of the belt *E* is opposed, and the projections *E*² are suitably pressed against the covers *b*, by the weight of a floating guide member *E*³, extending longitudinally of the chamber *C* and having uprising ears *E*⁴ vertically slotted to receive guide pins *C*⁴ carried by the side walls of the chamber *C*. To insure the proper relative 20 rates of travel of the conveyor belts *A* and *E*, and the proper relative positions of each container and the cooperating cover engaging part *E*², one of the pulleys *A'* and the adjacent pulley *E'* may be connected by gears *EA* proportioned to give 25 the same peripheral velocities to the pulleys *A'* and *E'*.

In the apparatus diagrammatically shown in Fig. 1, the belt *A* is employed to move the containers into and through the top heating zone, 30 after first moving them past a filling station, in which the charge of material to be sealed in each container is passed into the latter through a filling funnel or nozzle member *F*, and thence through a heating chamber *G*, and thence 35 through a capping station. As it passes through the capping zone, each container receives a cap or cover from the cap reservoir *H*, of a cover supplying mechanism, which may be of well known form. As shown, the reservoir has cover heating 40 means *H'* at its lower end.

The heating chamber *G*, as shown, has its bottom wall *G'* below the upper run of the conveyor belt *A*, the end walls of the chamber *G* being notched and slotted for the passage of the belt *A* 45 and the containers *B* carried by the latter. As shown, the chamber *G* is heated by steam discharged through perforated steam supply pipes *G*², located in the portion of the chamber below the conveyor belt *A*, which, with such chamber 50 heating provisions, is necessarily pervious for the upflow through it of steam. To minimize the outflow of steam from the chamber *G* and the inflow of air into the latter, suitable closure or baffle parts *G*³ may be provided at the openings in the end walls of the chamber *G* through 55 which the containers pass into and out of the latter. Each such part *G*³ may be in the form of flexible baffle curtain, such as is frequently employed in connection with such apparatus, which 60 tends to extend across and close the corresponding end wall opening, but is automatically displaced by the containers as required to accommodate 65 the movements of the latter.

In the use of the apparatus illustrated in Figs. 70 1 and 2, the foodstuff or other material to be preserved may be cooked or partially cooked prior to the container filling operation, and the heating action of the chamber *G* may serve an air expelling purpose only, or both an air expelling and cooking purpose. As will be apparent

to those skilled in the art, the described procedure gives advantages in addition to those already mentioned. For one thing, the location of the reservoir *H* and cover supply mechanism in the open, between the heating chamber *G* and top heating chamber *C*, makes the cover supply mechanism accessible for inspection and adjustment and reduces the interference with the normal operation of the apparatus necessarily resulting from a temporary interruption in the normal operation of the cover supply mechanism. The localized top heating action effected in the chamber *C*, expels air entering the upper portion of the container and its contents as the container passes from the heater *G* to the top heater 10 *C*, subjects the container cover to a sterilizing action, and contributes to an effective ultimate sealing of the container. In particular, the top heating action contributes to desirable sealing results by softening the rubber gasket, customarily 15 provided for sealing such containers as disclosed in the above mentioned patents. The desired effects of the top heating action can be attained more readily and with a smaller expenditure of heat by a localized top heating action than by a 20 reheating of the entire field container which, in some cases, might result in an undesirable overheating of the container contents.

In Figs. 3, 4, and 5, I have illustrated the addition to the top heating chamber *C*, of means 25 providing a movable bottom wall therefor, with apertures therein through which the upper portions of the containers extend into the chamber. As shown, the bottom wall is formed by a belt *I* having suitably spaced apertures *I'*, each adapted 30 to receive the upper portion of a container. When as may frequently be desirable, the top heating action is confined to container upper portions smaller in cross section than the adjacent body portion of the containers. Each aperture *I'* may 35 be of a diameter less than the diameter of the body portion of the container, and just sufficient for the protrusion therethrough of the portion of the container subjected to the top heating action.

As shown, the belt *I* runs over guide means at 40 the ends of the chamber *C* so disposed as to lower the portion of the belt *I* entering the chamber *C*, so as to cause each aperture *I'* to be entered by the top portion of a corresponding container *B*. At the end at which the containers leave the 45 chamber *C*, the guide means for the belt *I* are arranged to raise the portion of the belt moving away from the container to a level above the tops of the containers and their covers. The guide means shown, comprise a pulley or roller *J* and 50 guide rolls *K* at each end of the chamber. Each pulley or roller *J* has its upper belt engaging surface at the desired level of the top run of the belt. At each end of the chamber there are two pulleys *K* arranged to engage the upper sides of 55 the opposite edges of the lower run of the belt, the various pulleys *K* being above, and tangential to the horizontal lower portion of the belt *I*. The pulleys *J* are located at a greater distance from the ends of the chamber *C* than the corresponding pulleys *K* so that the lower portion of the belt *I*, includes an inclined portion extending from the level of the underside of the corresponding pulleys *K* to a level above that of the tops of the covers 60 on the containers *B* moving through the top heating zone. The belt *I* must have its travel proportional to that of the belt *A* and belt *E*. That result may be secured by a gear connection between a driving pulley or pulleys for the belt *I*, and the driving means for one or the other of the 65 70 75 80 85 90 95 100 105 110 115 120 125 130 belts A and E, but with the belts A and E driven in timed relation and with each container held in position at top and bottom by the parts E² and A³, the belt I can be advanced by the containers B with which it is in engagement.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. In packaging material in a vacuum sealed container, the method which consists in subjecting the upper portion of the filled container to a localized top heating action, while loosely holding the container cover in place to permit the escape of air and vapor from the container during the top heating operation and to permit the cover to be pressed into sealing engagement with the container, when, following the top heating operation, the pressure acting externally on the container becomes higher than the pressure within the container, and subsequent to said top heating action, subjecting said container to an external pressure exceeding the pressure within the container.

2. In packaging material in containers having vacuum sealed covers, the method which consists in moving the filled containers through a top heating zone in which the upper portion of each container is subjected to a localized heating action to expel air and vapor from the container and in loosely holding the covers for the containers in place thereon, as the containers pass through the top heating zone to permit of such cover lifting movements as are necessary for the expulsion of air and vapor and so as to insure the vacuum sealing of each container by an increase at the end of the top heating action in the pressure acting externally on the container, over the internal container pressure, and subsequent to said heating action, subjecting said container to an external pressure exceeding the pressure within the container.

3. Vacuum sealing apparatus comprising a heating chamber formed with openings in its wall for movement through the chamber of the upper portions of containers, conveyor means for supporting and moving said containers, and yielding means within said chamber acting on the covers for said containers to hold them loosely in place in the containers, and adapted to yield, to permit said covers to lift to accommodate the escape of air and vapor expelled from the containers by the top heat action, and to insure the vacuum sealing of each container when it passes out of said top heating zone and the pressure acting externally on the container becomes higher than the internal container pressure.

4. In packaging material to be preserved in a container having a vacuum sealed cover, the method which consists in filling the container and placing its cover in position and then in enveloping the upper ends of the containers in a

steam atmosphere so as to form vapor in the upper portions of the containers without materially increasing the temperature of the lower portions of the containers and the contents thereof, and subjecting the cover to force, tending to maintain the latter in its container closing position, but yielding to permit the escape of air and vapor from the container, and thereafter increasing the external pressure on the container relative to the internal container pressure, thereby forcing the cover into sealing engagement with the container.

5. Vacuum sealing apparatus comprising in combination, conveyor means adapted to support containers arranged thereon in a row and to move said containers in the longitudinal direction of the row, a top heating chamber above said conveyor means and formed with end and bottom wall openings for the movement through the chamber of the upper portions of the containers in said row, means for heating the portions of the containers within said chamber, and means for loosely holding covers in place on the containers to permit the escape of air and vapor from the containers as their top portions are passing through said chamber and to insure the movement of each cover into sealing engagement with the container as the latter passes away from said chamber and the pressure with the container diminishes below the pressure acting externally on the container.

6. Vacuum sealing apparatus comprising in combination conveyor means adapted to support containers arranged thereon in a row and to move said containers in the longitudinal direction of the row, a top heating chamber above said conveyor means and formed with end and bottom wall openings for the movement through the chamber of the upper portions of the containers in said row, means for heating the portions of the containers within said chamber, means for loosely holding covers in place on the containers to permit the escape of air and vapor from the containers extending into said chamber and to insure the movement of each cover into sealing engagement with the container as the latter passes away from said chamber and the pressure with the container diminishes below the pressure acting externally on the container, and means forming a movable bottom wall for said chamber and formed with permanent apertures through which the upper portions of the containers extend into said chamber.

7. In packaging material in a vacuum sealed container, the method which consists in filling the container with said material, heating the filled container, placing a container cover in closing position on the container, thereafter subjecting the upper portion of the filled container to a localized top heating action, while loosely holding the container cover in place to permit the escape of air and vapor from the container during the top heating operation and to permit the cover to be pressed into sealing engagement with the container, when, following the top heating operation, the pressure acting externally on the container exceeds the pressure within the container, and subsequent to said top heating action, subjecting said container to an external pressure exceeding the pressure within the container.

KARL L. FORD.
